UNITED STATES PATENT OFFICE.

JOHN B. IRVINE, OF SHERMAN, TEXAS.

WIRE-STRETCHER.

SPECIFICATION forming part of Letters Patent No. 316,039, dated April 21, 1885.

Application filed July 11, 1884. (No model.)

To all whom it may concern:

Be it known that I, JOHN B. IRVINE, a citizen of the United States, residing at Sherman, in the county of Grayson and State of 5 Texas, have invented certain new and useful Improvements in Wire-Stretchers; and I do hereby declare that the following is a full, clear, and exact description of the invention, which will enable others skilled in the art to 10 to which it appertains to make and use the same.

This invention relates to that class of wire stretchers or tighteners which are adapted to be applied upon the strands of wire forming a fence, and are used to tighten or stretch 15 the same by winding the strand about one end of the device and engaging the other end of the latter with the strand.

The object of my improvements is to provide a simple device of this class which will 20 possess advantages in point of inexpensiveness and durability of construction, and convenience, strength, and general efficiency in operation.

In the drawings, Figure 1 is a perspective view of a wire-tightener embodying my improvements. Fig. 2 is a longitudinal sectional view of the same. Fig. 3 is a transverse sectional view in detail, taken on a plane between the winding-pins. Fig. 4 is a side 30 view showing the device in position upon the wire.

Corresponding parts in the figures are denoted by the same letters of reference.

Referring to the drawings, A designates a 35 bar or lever, which forms the body of the wire-tightener, and is preferably flattened at one end, a.

From the face of the end a project two lateral pins, B B, formed integral with the body, 40 and disposed about centrally and in a longitudinal plane.

A small space, b², is left between the integral pins, and from the inner face of one of the pins projects an integral pin, b, extending 45 nearly across the space b², and disposed near the outer end of the pin B, which carries it. The other end of the bar or lever A is provided with the integral hook C, which projects laterally on a plane at right angles 50 with the pins B B.

My improved stretcher or fastener is preferably formed of cast or malleable iron, and is constructed in a single piece, all of its parts being integral, as shown.

The operation and advantages of my improved wire-stretcher will be readily understood by those skilled in the art to which it appertains. It can be manufactured at a comparatively small cost, and its construction, especially in the arrangement of the two simple lateral pins and the small pin projecting between the same, is exceedingly simple, and enables the device to be readily cast or formed in a single piece.

To stretch and tighten the wire, it is only 65 necessary to place the wire in the space b² between the pins B, (in which position it will be retained by the small pin b,) and then turn the device until the wire is wound to the desired extent upon the pins, when the hook C 70 is adjusted over the wire to secure the device in position thereon.

It is manifest that my improved wire-tightener is not only useful in repairing breaks and for tightening racked fences, but will answer 75 every purpose in constructing new fences that can be accomplished by more complicated and cumbersome devices of its class; and it is also manifest that in tightening the wire this improved form of tightener draws the latter from 80 both directions at the same time, thus accomplishing efficient action upon great length of wire.

I am aware that wire-stretchers have been 85 heretofore constructed of a bar or lever having a drum at one end, around which the wire is wound, and provided with a hook or catch at the other end, and also that in some constructions of this class of stretchers pins have been employed in lieu of the drum, and 90 I therefore do not broadly claim such construction.

I claim and desire to secure by Letters Patent—

As an improved article of manufacture, the 95 herein-described wire stretcher and tightener, comprising the bar or lever A, having the flattened end a, the cylindrical pins B B, projecting laterally from the face of flattened end, and arranged apart, as described, the 100

pin *b*, projecting laterally from the inner face of one of the pins *B*, near the outer end thereof, and extending nearly across the space between the pins, and the single curved hook-
5 piece *C*, projecting from the other end of the lever, substantially as and for the purpose set forth.

In testimony whereof I affix my signature in presence of two witnesses.

JOHN B. IRVINE.

Witnesses:

J. A. WILLSON,
JULIAN HEDRICK.
